(57) **CLAIM**

The ornamental design for a vehicle alarm pager, as shown and described.

DESCRIPTION

FIG. 1 is a front elevational view of the vehicle alarm pager of the present invention;

FIG. 2 is a rear elevational view of the vehicle alarm pager of FIG. 1;

FIG. 3 is a left side elevational view of the vehicle alarm pager of FIG. 1, the right view being a mirror image thereof; FIG. 4 is a top plan view of the vehicle alarm pager of FIG. 1; and,

FIG. 5 is a bottom plan view of the vehicle alarm pager of FIG. 1.

The broken lines showing of a speaker in FIG. 1 are for illustrative purposes only and form no part of the claimed design.
